APPARATUS FOR CASTING TYPE FURNITURE

Filed April 23, 1931

Inventor

Ashton G. Stevenson,

By R. D. Stockman

Attorney

UNITED STATES PATENT OFFICE

ASHTON G. STEVENSON, OF CHICAGO, ILLINOIS

APPARATUS FOR CASTING TYPE FURNITURE

Application filed April 23, 1931. Serial No. 532,335.

This invention relates to improvements in apparatus for casting type furniture, and more particularly to type furniture molds of the kind disclosed in my Patent 1,260,828, dated March 26, 1918.

In accordance with my prior invention, a core extends lengthwise of the space within the mold body, and due to the intense heat encountered and the length of the core member, the core has a tendency to expand and distort, resulting in more or less breakage and causing inaccurate furniture having varying thicknesses instead of uniform thickness.

The primary object of the invention is to reinforce the core so as to eliminate such disadvantage, and at the same time, to provide a core member which has a portion functioning as a part of the cap or cover of the mold.

With the foregoing and other objects in view which will appear as the description proceeds, the invention consists in the novel features hereinafter described in detail, illustrated in the accompanying drawing, and more particularly pointed out in the appended claims.

In the drawing,

Fig. 1 is a perspective view of my improved mold with the closure or front piece removed.

Fig. 2 is a front elevation of the same partly in vertical section.

Fig. 3 is a transverse sectional view on the line 3—3 of Fig. 2.

Fig. 4 is a bottom plan view of a portion of the improved mold core member.

The mold comprises the usual body 5 which is adapted to be secured to or mounted upon the ordinary wheel or disk in the usual manner. 6 designates the cap or cover which is secured to the body by the usual screws 7, or by screws through the periphery of the mold wheel.

In the space 8, within the mold body, where the slug is to be cast, a core 9 is located, the lower surface of which is preferably inclined upwardly and outwardly as shown at 10.

In accordance with the present invention, the core has integral ends 11 rigidly connect-

ed with a bar 12 which forms part of the core member and extends across the top of the space 8. This transverse cross bar forms a bridge portion for the core, and it is connected to the core proper by one or more supports 13, and furthermore, the bar 12 forms a portion of the cap of the mold. This construction reinforces the core and prevents breakage. A rivet or rivets 14, as shown in Figs. 3 and 4, passes through the bar 12, support 13 and core 9, for the purpose of rigidly securing the core to its bridge bar.

The upper and lower sides of the core 9 are spaced from the corresponding walls of the mold body and bridge bar 12, so as to form at the rear, an upper slot 15 and a lower slot 16. The molten metal under pressure, is introduced through the lower slot 16 when a piece of furniture is to be cast.

At the narrower or front edge of the core, I place notches, as shown at 17. Thus, when molten metal is introduced, that part of the metal standing in the said notches will form transverse supporting bridges between the top and bottom of the furniture.

To further prevent buckling of the core, I provide suitable means to effectively prevent such buckling. 18 represents a removable front piece or closure for the mold, which pieces is carried by a matrix block 19 which is supported by the matrix carrier in the usual manner. This closure 18 is provided with face pins 20 which extend into the mold body to form a front support for the core.

The core 9 and pins 20 (usually three in number), serve to displace sufficient metal to make the furniture comparatively light without sacrifice to strength because of the bridging bars which unite the top and bottom of the same, due to the notches 17.

Due to the reinforcement which I have provided for the core, the latter is positively prevented from distorting or breaking, and consequently, the furniture cast in a mold employing my improved core will always be of uniform construction.

From the foregoing it is believed that the construction and advantages of my invention may be readily understood by those skilled in the art, and I am aware that

changes may be made in the details disclosed, without departing from the spirit of the invention, as expressed in the claims.

What I claim and desire to secure by Letters Patent is:

- 5 1. In a mold of the character described, a mold body having a passage therethrough, closure means for the front end of said passage, a core for partially closing the rear end of said passage, a reinforcing bar, and a support rigidly uniting the core to the reinforcing bar.
- 10 2. In a mold of the character described, a mold body having a passage therethrough, closure means for the front end of said passage, a core for partially closing the rear end of said passage, a reinforcing bar, and a support rigidly uniting the core to the reinforcing bar, said support being positioned at the medial portion of the core.
- 15 3. In a mold of the character described, a mold body having a passage therethrough, closure means for the front end of such passage, a core for partially closing the rear end of said passage, a reinforcing bridge bar extending across and arranged above the core, a core support arranged between the bridge bar and core, and means rigidly uniting the support to the bridge bar and core.
- 20 4. In a core member for use with furniture molds, comprising superposed elongated bars spaced apart to form a longitudinal slot, one of said bars being tapered transversely and provided at its forward end with spaced notches to form a core, a support positioned between the midial portions of said bars and spanning said slot, and means rigidly uniting the support with the bars.

In testimony whereof, I hereto affix my signature.

ASHTON G. STEVENSON.
